UNITED STATES PATENT OFFICE

SAMUEL M. DOVER, OF CHICAGO, ILLINOIS

SIGNALING DEVICE

Application filed March 31, 1930. Serial No. 440,421.

My invention relates more particularly to signaling devices employing compressed air as the operating medium and more especially to signaling devices for use on vehicles.

My object is to provide a novel, simple, durable, and relatively inexpensive construction of signaling device of the character above stated and preferably of such construction as adapts it to be hand operated.

Referring to the accompanying drawings: Figure 1 is a broken view in longitudinal sectional elevation of the forward end of an automobile showing it as equipped with a signaling device embodying my invention.

Figure 2 is a view in side elevation of the signaling device.

Figure 3 is an end view of the device.

Figure 4 is a broken plan view of the device.

Figure 5 is a broken section taken at the line 5—5 on Fig. 2 and viewed in the direction of the arrows.

Fig. 6 is a section taken at the lines 6—6 on Figs. 3 and 7 and viewed in the direction of the respective arrows; and

Figure 7, a broken section taken at the line 7—7 on Fig. 2 and viewed in the direction of the arrows.

The signaling device shown comprises a casing 8 at which the device would be supported in any desirable position for use, in the arrangement shown, where it is illustrated as provided on an automobile, the casing 8 being secured to the top of the engine 9 by means of a bracket 10. It will be understood, however, that the casing 8 may be located, if desired, at any other suitable place and secured in position in any desirable way.

The casing 8 is formed of a central cylindrical member 11 open at its opposite ends and end disks 12 containing recesses 13 into which the ends of the member 11 extend, these parts being held together by screws 14 located at the margins of the disks.

The disks 12, which are of the same form and size, are each provided at its circumference with a hollow projection 15 which extends crosswise of the disk, one end of each projection 15 being of a width considerably greater than one-half the thickness of the

casing, as represented at 16, and the other end being of a width considerably less than one-half of the width of the casing, as represented at 17, the projection 15, in the assembling of the disks 12 with the member 11, being so disposed as to interfit with each other as shown more particularly in Fig. 3 in which position the larger portions 16 of the projections 15 are disposed in staggered relation.

The device also comprises compressed-air-operated sound-producing devices, which may be of any desirable type. Two such sound-producing devices, shown as constructed to produce different tones, are employed in the construction shown, these devices being represented at 18 and being screwed into the openings 19 in the portions 16 of the projections 15. The sound-producing devices 18 are open at the ends thereof at which they are screwed into the openings 19 and thus each opens into the one of the projections 15 in which it is secured.

The compressed air for operating the devices 18 is generated in the casing 8 of the device by a double-acting piston reciprocable in the member 11 as hereinafter described, the projection-equipped disks 12 containing openings therethrough for causing the interior of the member 11 to communicate at its opposite ends with the spaces in the projections 15, respectively, and with which the sound-producing devices 18 communicate. The opening above referred to and at one end of the member 11, for one of the devices 18 is represented at 20, its outer end being closed by a plug 21. The opening (not shown) for the other device 18, and corresponding with the opening 20, as will be understood from the foregoing, is located in the disk which is at the end of the casing 8 opposite that at which the disk 12 is located in Fig. 7 and opens into the projection 15 into which this particular device extends.

The piston above referred to is represented at 22 and is formed with a pair of cup leathers 23 disposed back to back and connected with a piston rod 24 which is slideable in an opening 25 in the center of one of the disks 12, a coil spring 26 surrounding the rod 24 and confined between the piston proper and

the opposite one of the disks 12 being provided to return the piston to the position shown in Fig. 5 following the actuation of the piston out of said position.

It will be understood from the foregoing description that when the piston 22 is moved to the left in Fig. 1, the air in front thereof will be compressed and forced out through one of the devices 18 thereby producing a tone and that when the piston is moved in the opposite direction it will operate to force air through the other device 18 and thus cause a tone to be produced thereby, the spring 26, as above stated, operating automatically to shift the piston in the last-referred-to direction.

In the arrangement shown the piston 22 is operated by hand from the dashboard of the automobile and represented at 27, the dashboard being shown as equipped with a rod 28 slidable therein provided at one end with a hand grip 29 by which it may be drawn on in a direction away from the casing 8 and a wire connection 30 between the rod 28 and the piston rod 24, the casing 8 being so arranged that pull on the rod 28 acts in the same general direction as that in which the rod 24 extends, whereby the piston 22 may be operated to force actuating air pressure to the device 18, alternately, merely by the operator pulling the rod 28 to shift it to the left in Fig. 1 and thereupon releasing his grasp upon the rod to permit the spring 26 to act.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. A signaling device comprising a piston-pump formed of a cylindrical member open at its opposite ends, closure-disks at the ends of said member and a piston in said member, said disks having portions extending cross-wise thereof and lapping said member at the exterior of the latter, and air-pressure-operated sound-producing devices connected with said portions, said device containing passages leading from the interior of said member into said sound-producing devices.

2. A signaling device comprising a piston-pump formed of a cylindrical member open at its opposite ends, closure-disks at the ends of said member and a piston in said member, said disks having portions extending cross-wise thereof and lapping said member at the exterior of the latter, and air-pressure-operated sound-producing devices connected with said portions, said device containing passages leading from the opposite ends of the interior of said member into said sound-producing devices, respectively.

3. In combination with a vehicle having an

instrument board, a signaling device located remote from said instrument board and comprising a pump, an air-pressure-operated sound-producing device in communication with said pump, and a pump-actuating element extending through, and slidable in, said instrument board.

4. In combination with a vehicle having an instrument board, a signaling device located remote from said instrument board and comprising a piston-pump, an air-pressure-operated sound-producing device in communication with said pump, and a pump-actuating element extending through, and slidable in, said instrument board.

5. In combination with a vehicle having an instrument board, a signaling device located remote from said instrument board and comprising a piston-pump the longitudinal axis of the piston of which extends substantially at a right angle to said instrument board, an air-pressure-operated sound-producing device in communication with said pump, and a pump-actuating element extending through, and slidable in, said instrument board.

6. A signaling device comprising a casing, a sound producing device communicating therewith and extending therefrom, and a piston mechanism operable in said casing and co-acting therewith to form a pump operable to actuate said device, said piston mechanism being movable on an axis substantially at a right angle to the longitudinal axis of said device.

7. A signaling device comprising a casing, a sound producing device communicating therewith and extending therefrom, and a piston mechanism operable in said casing and co-acting therewith to form a pump operable to actuate said device, said piston mechanism being movable on an axis substantially at a right angle to the longitudinal axis of said device, and means operable from a distance to actuate said mechanism.

8. A signaling device comprising a casing, a sound producing device communicating therewith and extending therefrom, and a piston mechanism operable in said casing and co-acting therewith to form a pump operable to actuate said device, said piston mechanism being movable on an axis substantially at a right angle to the longitudinal axis of said device, in combination with a vehicle and the instrument board thereof, and means located adjacent said instrument board and operable to actuate said piston mechanism.

SAMUEL M. DOVER.
